(57) **CLAIM**

We claim the ornamental design for a salt block, as shown and described.

DESCRIPTION

FIG. 1 is a top perspective view of a salt block of the present invention;

FIG. 2 is a top perspective view of another embodiment of a salt block of the present invention;

FIG. 3 is a top perspective view of another embodiment of a salt block of the present invention;

FIG. 4 is a top perspective view of another embodiment of a salt block of the present invention;

FIG. 5 is a top perspective view of another embodiment of a salt block of the present invention;

FIG. 6 is a top perspective view of another embodiment of a salt block of the present invention;

FIG. 7 is a top perspective view of another embodiment of a salt block of the present invention;

FIG. 8 is a top perspective view of another embodiment of a salt block of the present invention;

FIG. 9 is a top perspective view of another embodiment of a salt block of the present invention;

FIG. 10 is a top perspective view of another embodiment of a salt block of the present invention; and,

FIG. 11 is a top perspective view of another embodiment of a salt block of the present invention.

The broken lines in FIGS. 1-11 illustrate portions of the salt block that form no part of the claimed design.
